(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a front perspective view thereof in a condition that the cover is closed frontward; and,

FIG. 10 is a rear perspective view thereof in a condition that the cover is closed backward.

The broken lines shown in the figures that are immediately adjacent to the shaded areas and define unshaded regions represent the bounds of the claim. All other broken lines, including the features within broken line boundaries and the broken lines display rectangle on the front surface, the oblong sensors, circular camera features on the back, are directed to environment. The broken lines form no part of the claimed design.
